UNITED STATES PATENT OFFICE.

LESLIE R. McDONALD, OF MONTREAL, QUEBEC, CANADA.

STEREOSCOPIC X-RAY APPARATUS.

Application filed March 3, 1921. Serial No. 449,410.

To all whom it may concern:

Be it known that I, LESLIE R. McDONALD, a citizen of the United States, residing at Montreal, Province of Quebec, Dominion of Canada, have invented certain new and useful Improvements in Stereoscopic X-Ray Apparatuses, which I characterize as palmoscopes, of which the following is a specification.

10 My invention relates to improved means for observing conditions revealed by the use of the X-ray in the system which may be spoken of as X-ray stereo-fluoroscopy; and my improvements are directed particularly 15 to the production of a light, simple and efficient device which may be attached to the head of the observer, and through which he may look, very much as he would through a pair of goggles, but first with one eye and 20 then with the other in such rapid succession as to afford a stereoscopic view of the observed conditions; the alternate cutting off of the line of vision from one eye or the other being obtained by the use of vibratory 25 means, for which reason I describe my improved instrument as a palmoscope.

The details of my invention will more fully appear from the following description.

30 In the drawings, Fig. 1 is a front view; Fig. 2 is a side view, looking to the left on Fig. 1; and Fig. 3 is an end view, looking up on Fig. 2; Fig. 4 is a view similar to Fig. 1, but with the front casing removed; Fig. 5 35 is a side view, looking to the right on Fig. 4, the side casing however being removed and the head rest being partly in section; Fig. 6 is an end view, looking up on Fig. 4; Figs. 7, 8, 9 and 10 are details of supporting elements 40 for the vibratory member; Figs. 11 and 12 are, respectively, an edge view, and a side view of the soft steel elements of the cores for the electromagnets; Figs. 13 and 14 are similar views of the tempered steel elements for 45 the same magnets; Fig. 15 is a front view, with the front case removed, of a modification; Fig. 16 is a side view of the same, looking to the left on Fig. 15, the side casing, however, being removed, and the head 50 rest being partly in section; Fig. 17 is an end view of the same, looking up on Fig. 15; Fig. 18 is a diagrammatic sketch of the magnetic flux performance of the actuating magnets; Figs. 19 and 20 are details of the holding 55 mechanism for the vibratory member; and Fig. 21 is a diagrammatic plan of the elec-

tric circuits and operative elements which may be employed in utilizing the palmoscope.

Similar letters of reference designate similar parts in all the figures.

The several parts of my improved palmoscope are assembled upon a base 1, which carries a side casing 2, and the front casing or cover 3, having an apron 4 extending down over the lower part of the mechanism.

The base and casing are secured together by suitable means, such as studs 5 and cooperating bolts 6.

To the lower end of the base 1 I attach 70 a shield 7, preferably made of felt or some similar flexible material, and adapted in form to bridge the nose of the wearer and to contact with the adjacent part of his face so as to protect his eyes from lateral 75 glare, and, also, so as to cushion the palmoscope where it rests against the wearer's face. And to the back of the base 1, through the medium of flanges 8, 8, or other suitable means, I pivot a head rest 9, preferably provided with a flexible pad, as 10, and with arms 11, 11 which are attached by a suitable pivot 12 to the flanges 8 on the back of the base 1. The head rest is also provided with loops 13, 13 which are adapted to receive 85 the ends of a strap 14, shown in Fig. 3, by means of which the head rest may be secured to the head of the person using the palmoscope, so that the instrument may be swung up, if desired, that the user may look below 90 it, or it may be swung down so that the peep holes will be in line with his eyes.

The actuating mechanism of the palmoscope embodies substantially two electromagnets provided with cores preferably 95 built up of alternate plates 15, 15 of soft steel, and 16, 16 of tempered steel, respectively. The tempered steel elements of the two magnets are oppositely polarized, so that when an alternating current is sent 100 through the magnets one of them will respond actively to one phase of the impulses, and the other to the other phase. In other words, if we assume that the north pole of the right hand magnet, as shown in Fig. 105 4, is at the top, then the north pole of the left hand magnet will be at the bottom; and when an alternating current is sent through the magnets one of them will be energized by one phase of the current and the other 110 by the other phase. The coils 17, of the respective magnets, are energized by current

derived from the same source as that which illuminates the X-ray tubes, so that the alternations in the coils and in the tubes have the same periodicity and phases.

5 Thus, in Fig. 21, 20 and 27 represent the main line leading from and back to the source of the current, and one phase of the current passes from line 20 through line 21, transformer 22, 23, line 24, preferably 10 through an adjustable resistance 18, coils 17, line 25, transformer 23, 22, line 26 and main line 27 back to the source of supply; while the other phase of the current follows the reverse course. Also, from line 20 one 15 phase of the current passes simultaneously through the transformer 30, 31 line 32, tube 33, line 34, tube 35, line 36, transformer 31, 30 and line 27 back to the source of supply; and the other phase of the current follows 20 the reverse course. The tubes operate alternately, with an alternating current, due to the fact that they are rectifying tubes, and one tube gives out X-rays, under the influence of one phase of the current, and the 25 other tube gives out the X-rays under the influence of the other phase of current. When the palmoscope is in use the tubes, 33, 35 are located, as shown diagrammatically in Fig. 21, behind the object of observation, 40 30 which is in front of the screen 41, behind which is the observer, whose eyes are represented as looking through the palmoscope at 42, 43. Hence, at the instant the tube 33 is illuminated, and projects its rays through 35 the object under observation, 40, and casts its image on the screen 41, by means of my improved mechanism, as hereinafter explained, the image will be made visible by the observer's eye at 42, and will be invisible to 40 his eye at 43. While, when the tube 35 is illuminated, and the tube 33 is not, the image upon the screen 41 will be visible to the eye at 43 and not to the eye at 42.

To the upper portion of the base is firmly 45 secured a block 46, which is pierced at 47, 47 to receive anchor bolts, and at 48 to receive a set screw 49, the end of which projects into a bore 50, through which bore passes a shank 51, provided with a milled 50 head 52, and an annular groove 53, into which groove the point of the set screw 49 projects, (see Fig. 20), the lower end of the shank 51 being screw threaded to cooperate with another part of the apparatus 55 subsequently described. The block 46 is also tapped at 54 to receive a set screw 55 adapted to close a portion of the slot 56 when screwed home. The block 57 is also provided with a transverse slot 58. And 60 this block 57 cooperates with block 46, which is screwed to it and to the base 1 by means of anchor bolts 59, 59, passing down through both the blocks 46 and 57 and screwed into the base 1. The transverse slot 58 in block 65 57 is milled to receive a sliding block 60,

through which is threaded the shank 51, the block 60 being also provided with a transverse slot 61, disposed in line with the slot 56 in the block 46. A strip of thin steel 62 passes down through the slot 56 in block 70 46, and is held fixed therein by the set screw 55. The strip 62 also passes snugly through the slot 61 in the block 60, so that the free end of the strip, below the block 60, may be lengthened or shortened by sliding 75 the block 60 up or down along the strip, the rotation of the threaded shank 51 operating to raise or lower the block 60 through its housing 57. The strip 62 extends down between the poles of the electro magnets, the 80 lower poles of which are preferably provided with buffer lugs 63, 63, slotted at 64 to receive anchor bolts as shown which hold the ends of their respective magnets to the base, thereby permitting the buffer lugs to 85 be adjusted toward or away from each other when the bolts are slackened off.

To the lower end of the strip 62 I attach two shutter vanes 66, 67 which normally lie partially over the peep holes 68, 69 in the 90 base 1, preferably, however, leaving a narrow strip along the outer edge of each peep hole uncovered, as shown in Figs. 1 and 4, the result of this arrangement being that when the strip 62 is drawn to one side it 95 causes the vane on that side to cover the peep hole on that side; and when the deflection of the strip 62 is reversed it will cover the peep hole on the other side and uncover the first one.

100 It will be seen, therefore, that if the electro magnets are in circuit with two X-ray tubes, adapted to respond respectively to the opposed phases of an alternating current, one of the tubes and one of the magnets will be simultaneously energized by the same electrical impulse; and, for instance, if the magnet on the right side of the palmoscope is energized simultaneously with the flash of the tube opposite the left peep hole, the vibratory strip 62 will be pulled to the right, uncovering the left peep hole and closing the right one. And this movement will be reversed under the influence of the next electrical impulse; so that the vibratory strip 110 62, with its vanes 66, 67 will vibrate back and forth in synchronism with the flashes of the X-ray tubes, thus permitting the observer to have a stereoscopic-like view of the object under observation, the strip 62 being accurately adjusted or tuned to the requisite vibratory length by the lengthening or shortening of its free portion through the raising or lowering of the block 60, as already described.

115 In the diagrammatic view shown in Fig. 18, I have illustrated the magnetic performance of the actuating magnets. This diagram represents the flux condition at one alternation of a 60-cycle current, at which 120

instant the oscillating member would move to the left; while at the next alternation it would be attracted to and would move to the right; because the right hand magnet would at that instant have the strongest magnetic flux. This condition, however, only exists when the energizing, alternating current is at or below the critical point where its magnetic flux is equal to the residual magnetic flux of the tempered steel elements of the core of the magnet; and it is at its best when the soft steel elements have a cross section equal to twice the cross section of the tempered steel elements.

In Figs. 15, 16 and 17 I have illustrated a modification of my invention wherein two vibratory elements 70, 71 are used instead of the single element 62, the electro magnets being enlarged so as to increase their field sufficiently to actuate both of the vibratory elements, each of which is provided with a pair of vanes 72, 73 and 74, 75 respectively, these vanes being adjusted so that normally their adjacent edges do not quite meet, but leave a narrow slit over each of the peep holes in the base. The strips 70, 71 are, moreover, adapted, by permanent polarization, or otherwise, to be separately attracted in opposite directions by the electro magnets; and under the influence of an alternating current they will be simultaneously moved in opposite directions, alternately covering and uncovering first one and then the other of the peep holes. This arrangement slightly increases the rapidity of opening and closing the peep holes; and it also has the advantage of expanding the field of vision in both directions as the peep holes open, assisting to that extent the clearness of the observer's vision.

In the case of the modification shown in Figs. 15, 16 and 17, the holding and regulating blocks 80, 81 and 82 are made deeper than the blocks 46, 57, 60 and are so proportioned as to properly hold the free ends of the strips 70, 71 in close proximity to, but not in contact with each other. Suitable blocks, as 83, 83 may be interposed between the strips 70, 71, so that both strips 70, 71 may be locked in place by the same set screw 84.

It will be seen that by means of my improvements I secure a simple, compact and efficient instrument for observing X-ray images, and one which is light and easily worn by the observer, thus leaving both of his hands free for other uses, and also permitting great freedom of movement by the observer in connection with his work. The instrument, also gives a clear and distinct stereoscopic view of the object under observation, so that the observer if, for instance, he is a surgeon, can see in true perspective the conditions existing, and can, therefore, deal with them with a clear and compre-

hensive appreciation of their actual character.

It will be readily understood by those skilled in the art, that details of my palmoscope may be modified, as by the use of 70 mechanical equivalents, without departing from the scope of my invention as claimed.

Having thus described my invention, what I claim and desire to secure by Letters Patent of the United States, is:—

1. In an apparatus for observing X-ray images, the combination, with a source of alternating current, of means for producing, by the upper half of the current wave, a series of such images projected from one angle and alternating with a similar series produced by the lower half of said current wave and projected from another angle, and means, actuated by the alternating current, movable in one direction simultaneously with each impulse of the upper half of the current wave, and moveable in the opposite direction simultaneously with each impulse of the lower half of such current wave, for limiting the view of one series of such images to one point of observation, and of the other series to another point of observation.

2. In an apparatus for observing X-ray images, the combination, with a source of 95 alternating current, of means for producing, by the upper half of the current wave, a series of such images projected from one angle and alternating with a similar series, produced by the lower half of said current 100 wave and projected from another angle, and vibratory means, actuated by the alternating current, moveable in one direction simultaneously with each impulse of the upper half of the current wave, and moveable in 105 the opposite direction simultaneously with each impulse of the lower half of such current wave, for limiting the view of one series of such images to one point of observation, and of the other series of another 110 point of observation.

3. In an apparatus for observing X-ray images, the combination, with a source of alternating current, of means for producing, by the lower half of the current wave, 115 a series of such images projected from one angle and alternating with a similar series, produced by the lower half of said current wave and projected from another angle, and means, moveable in one direction by and simultaneously with each impulse of the upper half of the current wave, and moveable in the opposite direction by and simultaneously with each impulse of the lower half of such current wave, for limiting the 125 view of one series of such images to one point of observation, and of the other series to another point of observation.

4. In an apparatus for observing X-ray images, means for producing a series of 130

such images projected from one angle and alternating with a similar series projected from another angle, and resilient, vibratory means provided with shutters for limiting 5 the view of one series to one point of observation, and of the other series to another point of observation.

5. In an apparatus for observing X-ray images, means for producing a series of such 10 images projected from one angle and alternating with a similar series projected from another angle, and resilient, vibratory means for limiting the view of one series to one point of observation, and of the other series to another point of observation, and electrically energized means for actuating the vibratory means in synchronism with the production of the images.

6. In an apparatus for observing X-ray 20 images, means for producing a series of such images projected from one angle and alternating with a similar series projected from another angle, and vibratory means, embodying an elastic armature, disposed between 25 oppositely polarized electro magnets, for limiting the view of one series to one point of observation, and of the other series to another point of observation.

7. In an apparatus for observing X-ray 30 images, means for producing a series of such images projected from one angle and alternating with a similar series projected from another angle, and vibratory means embodying an elastic armature, disposed between 35 oppositely polarized electro magnets, and provided with vibration regulating means, for limiting the view of one series to one point of observation, and of the other series to another point of observation.

40 8. In an apparatus for observing X-ray images, means for producing a series of such images projected from one angle and

alternating with a similar series projected from another angle, resilient, vibratory 45 means, and means for detachably attaching the vibratory means to the head of an observer for limiting the view of one series to one point of observation, and of the other series to another point of observation. 50

9. In an apparatus for observing X-ray images, means for producing a series of such images projected from one angle and alternating with a similar series projected from another angle, and vibratory means 55 for limiting the view of one series to one point of observation, and of the other series to another point of observation, and a case containing said vibratory means and provided with observation openings, and with 60 means for detachably attaching it to the head of the observer.

10. In an apparatus for observing X-ray images, means for producing a series of such images projected from one angle and 65 alternating with a similar series projected from another angle, and vibratory means, embodying an elastic armature disposed between oppositely polarized electro magnets built up of alternate plates of soft steel and 70 tempered steel, for limiting the view of one series to one point of observation, and of the other series to another point of observation.

11. In an apparatus for observing X-ray 75 images, means actuated by an alternating electrical current for producing two alternating series of images projected from different angles, and resilient, vibratory means actuated by alternations from the same electrical current, for limiting the view of one series of images to one eye of an observer, and of the other series of images to his other eye.

LESLIE R. McDONALD.
